Primary Examiner — Mitchell I. Siegel(74) *Attorney, Agent, or Firm* — Werschulz Patent Law, LLC; Patricia P. Werschulz, Esq.(57) **CLAIM**

The ornamental design for a binding bag, as shown and described.

DESCRIPTION

FIG. 1 is a perspective view of a binding bag, showing my new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a right side elevational view thereof; and,

FIG. 7 is a left side elevational view thereof.

The broken lines showing in FIGS. 1 through 7 are for the purpose of illustrating the environment of the article only and form no part of the claimed design.

1 Claim, 4 Drawing Sheets(56)
